HUMIDIFIER

Edgar E. Wayles, East Hartford, Conn.

Application May 12, 1932, Serial No. 610,886

7 Claims. (Cl. 237—78)

This invention relates to humidifiers of a type wherein certain elements together with a porous sheet material are associated with pipes or conduits such as comprise the various forms of radiators commonly employed for heating living compartments. A film of liquid brought into contact with a heated surface as of a radiator pipe is quickly vaporized. Vapor thus produced and discharged into a flue arranged to induce a current of air is immediately diffused into surrounding atmosphere. The object of my invention is the provision of means for thus forming and diffusing vapor. Broadly the invention consists in the association of porous sheet material with laterally spaced pipes, said material being applied in direct contact with the pipes and in a manner to form a passageway which is open at both ends and through which the pipes extend so that space between the pipes provides a flue for a free current of air, and means for supplying liquid to the porous material. Advantages of the simple structure comprising the invention are fully set forth in the following detailed description in which reference is made to the accompanying drawings wherein as illustrated one convenient form of embodiment of the invention.

In the drawings,—

Figure 1 is a front view of a radiator with which is associated humidifying means and an enclosing casing, the latter being indicated as partly broken away and partly in section.

Figure 2 is a sectional view on line 2—2 of Fig. 1.

Figure 3 is a sectional view on line 3—3 of Fig. 1.

Figure 4 is a detail view of the skirt portion of a casing.

Figure 5 is a detail view of a panel for closing an opening in the casing.

Figure 6 is a detail view in perspective showing a modified form of means for conducting liquid to porous material associated with radiator sections.

A radiator of suitable form to receive and support apparatus comprising my invention may be of the well known and extensively used type illustrated wherein are a series of sections 2 each formed of laterally spaced pipes or conduits as 3 which are united by separated transversely disposed conduits as 4 and 5. The end sections of the radiator are respectively provided with inlet and outlet pipes 6 and 7 whereby provision is made for circulating a heating fluid through the numerous radiator passages of which the walls

present extensive exterior surface for radiating heat.

To provide a desired percentage of vapor in the air adapted to be heated by the radiator, means are employed for conducting liquid into contact and close proximity to a suitable area of the radiating surface mentioned. Such means comprise porous material applied directly to the heating surface. Linen fabric is suitable for this purpose and may be applied as a narrow strip wound in a spiral bandage and enclosing several of the pipes or conduits 3, or as shown, a sheet of the fabric may be wrapped around the conduits and fastened together with a longitudinally extending seam to form an enclosing tube 8 which

may then be tensioned upon the conduits by any suitable means. An effective arrangement for this purpose includes exterior longitudinally placed rods as 10 and 11 and transversely disposed bolts as 12 and 13 extending through the rods and between appropriate sections of the radiator. To maintain a yielding tension upon the fabric tube 8 to compensate for such stretching or shrinking as may take place, short springs as

14 may be placed under the head of each bolt. Any suitable arrangement may be provided for conducting and distributing water to the fabric tube 8. As shown a plate 15 of metal or other suitable material is placed upon the top of radiator sections of which the conduits are surrounded by tube 8. Overlying this plate is the central portion of a wick 16 from which extend any desired number of leaders 17 which may be fastened at their extremities to tube 8 as by stitching. Water for delivery to wick 16 may

be contained in an adjacent tank or as shown a supply pipe 18 may be provided and fitted with a regulatable drip cock 19. For enclosing the entire radiator a casing may be provided or if preferable certain sections only may be covered including those to which the liquid conducting porous material is applied. As shown a casing encloses four sections including one on each side of those supporting the porous material. This casing, preferably of sheet metal, may comprise a skirt portion 20, panels 21 and 22 and a bottom closure or drip pan 23. The skirt portion 20 includes a perforated top 24 which may be integral or separate therefrom.

Opposite sides of the casing skirt portion 20 are provided with openings as 25 and 26 to receive respective panels 21 and 22. The edges of the openings and panels, designed to engage each other, are preferably formed to make tongue and groove joints so that when the panels are placed

50
55

in position between the transverse conduits 4 and 5 the skirt portion 20 may be placed thereabove and telescopically slipped into engagement with the panels. The upper end of each opening 5 25 and 26 is formed to approximately fit the upper conduit 4 and the lower end of each panel 21 and 22 is formed to approximately fit the lower conduit 5 so that the casing when assembled on the radiator makes a flue substantially closed at the 10 sides except for perforations 27 which are provided near the bottom of the skirt to admit a current of air. When the skirt and panel portions of the casing have been assembled the drip pan 23 may be readily secured to the skirt as by screws 15 28. The ends of the drip pan are formed to fit around the lower conduit 5 and at one end of the pan there is connected thereto a drain pipe 29.

The functions promoted by the described structure are performed as follows: Water from drip 20 cock 19 falling upon wick 16 is conducted by the leaders from the latter to the fabric tube 8. Permeating the interstices of the fabric the water is spread over a large area and brought both directly into contact with the heated surface of 25 conduits 3 and in close proximity thereto so that it is quickly vaporized in comparatively large volume. Coming into contact with the heated surface of the radiator, currents of air are continuously induced within the tube 8 itself which 30 forms a flue between the tube enclosed pipes and within the casing which forms a flue surrounding the tube so that both the inner and outer surface of the saturated fabric are traversed by the air currents which directly take vapor where it is 35 generated and impel it upward and out through perforations of the top 24 and thence into diffusion through the atmosphere. Any water in excess of an amount which the fabric tube will support for vaporization passes downwardly into 40 drip pan 23.

In the modified form of means (shown in Fig. 6) for conducting liquid to porous material 30 associated with the intermediate portion of radiator sections 31 and 32, there is provided for each 45 section a hood as 33, also of porous material, closely fitting over the top of its respective section. A plate 34 is supported over these hoods and overlying the plate is a wick 35 having the short leaders as 36 by which liquid is carried to the hoods and distributed thereover to saturate the entire 50 hood as well as the tube adjoined thereto below. Obviously the advantage of this arrangement is that a greater portion of heating surface is utilized for vaporizing liquid.

Having thus described my invention, what I 55 claim is—

1. An apparatus for humidifying heated air, including in combination with a radiator, of the type wherein a plurality of connected sections 60 are formed of laterally spaced pipes or conduits, a tube of flexible porous material surrounding the intermediate portion of certain of the sections, resilient means for holding the porous material in contact with the enclosed sections, and means for supplying liquid to the porous material.

2. An apparatus for humidifying heated air, including in combination with a radiator of the

type wherein a plurality of connected sections are formed of laterally spaced pipes or conduits, a tube of flexible porous material surrounding the intermediate portion of certain of the sections, rods extending longitudinally of the tube along its outer surface, adjustable means connecting the rods to tension the porous material upon its supporting sections, and means for supplying liquid to the porous material.

3. An apparatus for humidifying heated air, including in combination with a radiator of the type wherein a plurality of connected sections are formed of laterally spaced pipes or conduits, a tube of porous material surrounding the intermediate portion of certain of the sections, means for holding the porous material in contact with the enclosed sections, a plate supported above the porous material, a wick overlying the plate and arranged to conduct liquid to the porous material, and means for supplying liquid to the wick.

4. An apparatus for humidifying heated air, including in combination with a radiator of the type wherein a plurality of connected vertical pipes or conduits are arranged in laterally spaced relation, porous material associated with certain 25 of the pipes in direct contact therewith and in a manner to form an open ended passage through which the pipes extend so that space between the pipes provides a vertical flue for a free current of air, means leading from above the porous material for directing liquid thereto, and means for receiving excess liquid delivered to the porous material.

5. An apparatus for humidifying heated air, including in combination, laterally spaced vertical pipes or conduits, porous material associated with the pipes in direct contact therewith and in a manner to form an open ended passage through which the pipes extend so that space between the pipes provides a vertical flue for a free current of air, and means for supplying liquid to the porous material.

6. An apparatus for humidifying heated air, including in combination with a radiator of the type wherein a plurality of connected sections are formed of laterally spaced pipes or conduits, a tube of porous material surrounding the intermediate portion of certain of the sections, means for holding the porous material in contact with the enclosed sections, a hood of porous material adjoined to the tube and associated with each section surrounded by the tube, a plate supported above the porous material, a wick overlying the plate and arranged to conduct liquid to the porous material, and means for supplying liquid to the wick.

7. An apparatus for humidifying heated air, including in combination with a radiator of the type wherein a plurality of connected sections are formed of laterally spaced vertical pipes or conduits, a tube of porous material surrounding the intermediate portion of certain of the sections, means for holding the porous material in definite relation to the enclosed sections, and means for supplying liquid to the porous material.

EDGAR E. WAYLES.
